(57) **CLAIM**

The ornamental design for wooden basket, as shown and described.

DESCRIPTION

FIG. 1 is a perspective view of the wooden basket showing our new design;

FIG. 2 is a front view thereof;

FIG. 3 is a rear view thereof;

FIG. 4 is a left side view thereof, the right side being a mirror image of the left side;

FIG. 5 is a top view thereof with the handles in an alternate position;

FIG. 6 is a bottom view thereof with the handles in an alternate position;

FIG. 7 is a perspective view of another embodiment of our design, having an appearance identical to that FIG. 1 except for the presence of color contrast;

FIG. 8 is a perspective view of another embodiment of our design;

FIG. 9 is a front view thereof;

FIG. 10 is a rear view thereof;

FIG. 11 is a left side view thereof;

FIG. 12 is a right side view thereof;

FIG. 13 is a top view thereof with the handles in an alternate position;

FIG. 14 is a bottom view thereof with the handles in an alternate position;

FIG. 15 is a perspective view of another embodiment of our design, having an appearance identical to that of FIG. 8 except for the presence of color contrast;
FIG. 16 is a perspective view of another embodiment of our design;
FIG. 17 is a front view thereof;
FIG. 18 is a rear view thereof;
FIG. 19 is a left side view thereof, the right side being a mirror image of the left side;
FIG. 20 is a top view thereof with the handles in an alternate position;
FIG. 21 is a bottom view thereof with the handles in an alternate position;
FIG. 22 is a perspective view of another embodiment of our design, having an appearance identical to that of FIG. 16 except for the presence of color contrast;

FIG. 23 is a perspective view of another embodiment of our design;
FIG. 24 is a front view thereof;
FIG. 25 is a rear view thereof;
FIG. 26 is a left side view thereof, the right side being a mirror image of the left side;
FIG. 27 is a top view thereof with the handles in an alternate position; and
FIG. 28 is a bottom view thereof with the handles in an alternate position; and,
FIG. 29 is a perspective view of another embodiment of our design, having an appearance identical to that of FIG. 23 except for the presence of color contrast.
